(57) **CLAIM**

The ornamental design for a welding machine housing, as shown and described.

DESCRIPTION

FIG. 1 is a perspective view of a welding machine housing showing our new design as seen from the upper front right hand side.

FIG. 2 is a perspective view of the housing as seen from the upper rear right hand side.

FIG. 3 is a perspective view of the housing as seen from the upper front left hand side.

FIG. 4 is a top plan view of FIG. 1; and,

FIG. 5 is a perspective view of the housing as seen in FIG. 3.

The broken line showings of other portions of the welding machine in FIGS. 1-4 are for illustrative purposes only and form no part of the claimed design.
